UNITED STATES PATENT OFFICE.

WESLEY PHILLIPS, OF MORRISANIA, NEW YORK.

IMPROVEMENT IN SPARK-ARRESTERS.

Specification forming part of Letters Patent No. 148,137, dated March 3, 1874; application filed January 10, 1874.

To all whom it may concern:

Be it known that I, WESLEY PHILLIPS, of Morrisania, in the county of Westchester and State of New York, have invented a new and useful Improvement in Spark-Arresters, of which the following is a specification:

The present invention relates to new and useful improvements in spark-arresters for steam-boilers, more especially designed for locomotive-boilers, but adapted to stationary and marine boilers; and consists of a sectional flare-pipe inside of a lower screen-pipe formed of wire-gauze, or wire cloth, and in a wire-gauze, or screen, or pipe, which rests on the bottom of the smoke-box, and in another tube or pipe of wire-netting at or near the top of the smoke-stack. It also consists in the arrangement and combination of parts, herein-after described, by which an open exhaust is obtained.

In the drawing, Figure 1 is a vertical section of Fig. 2 taken on the line *x x*, and Fig. 2 is an elevation, showing a portion of the boiler in section.

Similar letters of reference indicate corresponding parts.

A represents the boiler. *B* is the smoke-box at the end of the boiler. *C* is the smoke-flue. *E* is the steam-exhaust nozzle. *F* is a flare-pipe, composed of sections *G*, connected together by vertical straps with an annular opening around the top of each. This flare-pipe is surrounded by an open pipe, *I*, (which is designed to protect,) made of wire-cloth, or similar material. The open-work pipe *I* is connected with the lower end of the smoke-pipe *C*. The smoke-pipe *C* is surrounded by the pipe *J*, which pipe has a flaring base, *K*, which receives the sparks and smoke as they come from the flues of the boiler, as indicated by the arrows 2. *L* is an annular space between the smoke-flue *C* and the pipe *J*. As the products of combustion enter this space they are screened or strained through the wire-cloth pipe *I* by the vacuum produced, leaving the sparks and other solid particles in the space *L*, while the smoke or gaseous products enter the smoke-pipe and are carried up by the exhaust. The sectional flare-pipe is placed within the wire pipe *I*, to prevent the steam

from injuring that pipe. *M* is a pipe made of woven wire, or equivalent material, which is placed at the top of the stacks. The exhaust will create a draft through this pipe which will draw the sparks upward with much force. *N* is a semicircular cap on the top of the smoke-pipe *C*, against the lower concave side of which the sparks strike and drop by their own gravity to the bottom of smoke-pipe *C*, from which they are removed through the discharge-tubes *P P*. The arrows 2, indicate the course of the sparks, and the arrows 1 the course of the smoke and exhaust.

It will be seen that, by this construction and arrangement, a direct open exhaust is obtained. The smoke and gaseous products of combustion are separated at the base or in the smoke-box, while the sparks are delivered at the base of the smoke-stack, from whence they are readily removed.

Having thus described my invention, I claim as new and desire to secure by Letters Patent—

1. In combination with the reticulated pipe *I*, steam-jet nozzle *E*, and pipe *C*, the surrounding closed pipe *J*, extending into the casing or spark-receptacle *O*, and open at both ends, substantially as herein shown and described, and for the purpose specified.

2. In combination with the reticulated pipe *I*, surrounding tube *J*, and exhaust-nozzle *E*, the superposed concentrically-arranged short tubes or frustums of cones *F*, for creating a draft and for preventing the steam from acting directly upon the pipe *I*, as and for the purpose specified.

3. In combination with the smoke-discharge pipe *C* and stacks, the reticulated cylinder *M*, located at the top of the stack, as and for the purpose specified.

4. The smoke-discharge pipe *C*, provided with a deflecting cap, *N*, at its upper end, arranged in proper respect to the discharge end of the spark-conducting pipe *J* and the casing or spark-receptacle *O*, as herein shown and described.

WESLEY PHILLIPS.
